UNITED STATES PATENT OFFICE.

CARL C. YOUNG, OF RUSHVILLE, ILLINOIS.

COMBINED SCAFFOLD AND DERRICK.

1,347,430.

Specification of Letters Patent. Patented July 20, 1920.

Application filed March 26, 1919. Serial No. 285,330.

To all whom it may concern:

Be it known that I, CARL C. YOUNG, a citizen of the United States, residing at Rushville, in the county of Schuyler and State of Illinois, have invented certain new and useful Improvements in Combined Scaffolds and Derricks, of which the following is a specification.

This invention is a combined scaffold and derrick for use by masons and similar artisans and is intended more particularly for use in building circular silos. The invention comprehends the provision of means for supporting a platform within the space defined by the walls of the silo and raising the platform as the height of the silo increases; it also comprehends the provision of a derrick or hoisting mechanism which may be likewise raised as the silo rises in height and which will furnish means for hoisting the blocks or stones of which the silo wall is built. The invention also comprehends means for bracing the platform within the silo and seeks to provide an apparatus for the stated purpose which will be inexpensive and may be easily manipulated.

The invention is illustrated in the accompanying drawings, in which—

Figure 1 is a view in elevation of an apparatus embodying the improvements and showing the position of the same relative to a partly finished silo;

Fig. 2 is a perspective view of an anchor block which is employed in the practical operation of the invention;

Fig. 3 is a detail section of the anchor block;

Fig. 4 is a detail section on the line 4—4 of Fig. 1;

Fig. 5 is a view partly in plan and partly in horizontal section on the line 5—5 of Fig. 1;

Fig. 6 is a view showing the platform support in plan and showing the central mast and support in horizontal section;

Fig. 7 is a view, partly in elevation and partly broken away, of the central mast and the parts mounted directly thereon;

Fig. 8 is a perspective view of one of the platform supports and braces;

Fig. 9 is an enlarged detail vertical section of a portion of the derrick support;

Fig. 10 is a detail elevation of a portion of the mechanism for raising the platform and derrick;

Fig. 11 is a detail perspective view of the vertically movable frame or carrier.

In carrying out my invention, I employ an anchor block 1 which may be of any desired or convenient dimensions and will preferably have an angular vertical bore, indicated at 2. Having selected the site for the silo, the anchor block is firmly embedded in the ground at the center of the selected location, and a cap plate 3 is fitted in the upper end of the anchor block, the said cap plate being provided with a central pin 4 which may be engaged by any suitable tool or means for describing a circle thereabout. For instance, an extensible rod or bar may be pivotally engaged at one end over the said pin and at its other end provided with any form of tooth or cutter which will penetrate the ground sufficiently to mark off the location of the silo foundation when the bar or rod is swung pivotally about the pin 4. The same or similar means may be employed to bring the upper surface of the foundation to the desired level smooth condition after the foundation trench has been filled and while the foundation is setting. After the foundation has been formed and sufficiently set, the cap plate is removed from the anchor block and a mast 5 has its lower end fitted in the block so as to rise vertically therefrom, as shown in Fig. 7. This mast will be preferably a pole of angular cross section which will fit closely within the angular bore 2 of the anchor block so that it will be prevented from having relative turning movement and it will be constructed in sections which may be spliced together, as shown at 8, as the silo rises so that the platform and derrick or hoisting mechanism may be raised as the work progresses and the workmen supported within the silo at a proper height for conveniently performing the operation of setting the blocks or stones and raising them to their positions. The mast will obviously be located at the center of the silo and the platform which will be mounted thereon will, therefore, serve partly as a gage to determine whether the wall is plumb and thereby facilitate the building operation.

Fitted about the mast is a frame comprising an upper tubular portion 9, a lower tubular portion 10, and side bars 11 connecting the said upper and lower tubular portions. The tubular members are prefer-

ably circular in their exterior outlines and the lower member 10 is provided near its upper extremity with an annular groove 12, the function of which will presently appear, and near the lower extremity of said member is a similar groove 13. Secured upon the exterior surface of this lower tubular member are bands 14 which are provided with vertically disposed slots 15, the 5 slots in the lower band registering with the groove 13 and the slots in the upper band registering with the annular groove 12, the width of said groove 12 being greater than the length of the slots whereby the upper 10 band will extend over the upper portion of the groove, as clearly shown in Fig. 7. The lower tubular member 10 and the bands 14 mounted thereon carry the platform supports which may be of any desired number, 15 eight being illustrated in the accompanying drawings. These platform supports consist each of an upper beam 16, a lower beam or foot-bar 17, and vertical and oblique braces 18 and 19 extending between the 20 members 16 and 17. The beams 16 and the base or foot-piece 17 each consists of a pair of spaced bars having the ends of the braces secured rigidly between them with the vertical braces spaced from the inner extremities 25 of the said members. Blocks 20 are secured between the members of the beams and of the bases and project inwardly beyond the same to provide tenons or tongues 21 which are adapted to enter the several slots 15 and 30 the groove 13 or the groove 12 as the case may be. On the upper side of the upper block 20, I secure a retaining member 22 provided at its inner end with a lip or hook 23 which is adapted to engage behind the 35 overhanging portion of the upper band 14 and thereby prevent the platform-supporting member from falling outwardly from the member 10. To mount the platform supports in position, the supports are tilted 40 slightly so that the lip or hook 23 may be passed through the slot 15 into the groove 12, after which the support is swung downwardly so that the tenons or tongues 21 will enter the respective slots as will be readily 45 understood. The tenons or tongues should be of such dimensions that they will fit closely within the slots 15 so that vertical or lateral movement of the platform supports will be prevented, while, as stated and 50 as will be readily understood, outward movement of the said supports will be prevented by the engagement of the lips or hooks 23 behind the upper band 14. The platform supports will extend radially from the tubular member 10 and boards are to be placed 55 upon the supports so as to extend across the same as will be readily understood. The alternate floor supports are utilized as braces and to this end they are provided with levers 60 24 which are each pivoted at its inner end be-

tween the outer extremities of the parts of the respective base 17 and the said inner extremities of the levers are beveled, as shown most clearly in Fig. 1, whereby they will fit against the outer edges of the inclined braces 70 19 and be thereby prevented from swinging downwardly. These lever braces 24 are of such length that their outer extremities bear against the inner surface of the completed portion of the silo wall, as shown in 75 Fig. 1, and they thereby serve to maintain the mast in its central position relative to the silo wall and also aid in preventing sagging or bending of the mast. At an intermediate point of the length of each lever 80 brace 24, I pivotally attach the lower end of a locking bar 25 which extends upwardly between the parts of the beam 16 and is provided with a longitudinal series of openings 26 through any one of which a pin or bolt 85 27 may be inserted to secure the bar to the said beam 16. By varying the angular position of the lever brace it may be adjusted to silos of different diameters so that a single set of platform supports may be used for 90 silos of various dimensions. A filler 28 is secured between the parts of the beams 16 at the outer side of the locking bar 25 which plays between the said filler and the upper end of the brace 19, as shown, and between 95 the outer extremities of the beam 16 I pivot a tongue or extension 29 which has its inner end beveled to engage against a correspondingly beveled surface of the filler so that downward movement of the said tongue or 100 extension will be prevented. By providing a plurality of these extensions which differ in length the beams 16 may be made to carry platforms of various sizes according to the diameter of the silo under construction. The extensions or tongues 29 will terminate short of the silo wall, as shown in Fig. 1, so that the mason will not be hampered in setting the stones or blocks and may apply 105 his tools to all corners and surfaces thereof 110 without inconvenience or any liability to be precipitated to the bottom of the silo.

At an intermediate point of the bars 11, openings are provided therethrough to receive a bolt 30 which passes through the 115 mast and thereby serves to hold the platform supporting structure against vertical movement so that dropping of the platform and its support will be prevented. It will be understood, of course, that the mast will 120 be provided with openings at intervals along its height or length to receive the bolt or pin 30 so that the supporting structure may be secured to the mast at the proper point as the progress of the work necessitates.

The upper tubular member 9 constitutes a derrick support and is provided at its extremities with annular grooves, as indicated at 31, to receive the heads 32 which carry the derrick and are rotatably fitted to the 130

said grooves, the heads being preferably square in plan view and connected by bolts 33 extended through their corners so that the heads may rotate together and will 5 always be in the same relative position. The lower head is provided with projecting sills 34 upon which are pivotally mounted the standards 35 of the derrick, the said standards converging upwardly and outwardly 10 and being held in any desired adjusted position relative to the upper tubular supporting member 9 by a cable or similar brace 36 secured to and extending between the upper head and a cross-bar 37 near the upper 15 ends of the standards as will be readily understood. A derrick beam 38 extends outwardly from the upper ends of the standards 35 and braces 39 are secured to the said beam and the standards 35 so as to 20 impart the necessary rigidity to the structure. At the outer extremity of the beam 38 is an eye or anchor 39' to which the end of the hoisting cable 40 is secured and on the under side of the beam are pulleys 25 41 over which the cable runs, that portion of the cable between the anchor 39' and the outermost pulley 41 carrying a block and tackle 42 which is to be engaged in or connected with the stone or building block to 30 raise the same to the position where it may be set by the mason. From the inner guide pulley 41 the cable 40 extends downwardly to a drum or windlass 43 carried by and mounted between the standards 35 near the 35 lower ends of the same and on one end of the windlass shaft 44 is a sprocket 45. A chain 46 is trained around the said sprocket 45 and the inner member of a double sprocket 47 while a chain 48 is trained around the 40 outer member of said double sprocket and a larger sprocket 49 secured on a shaft mounted in a suitable bearing in a sill 34 and provided with an operating handle 50.

The bore of the member 9 is cruciform 45 in outline thereby providing spaces 51 at the sides of the mast 5 to accommodate cables 52 each of which is secured at one end to a rod 53 carried by projections 54 on the side bars 11 of the slidable support. 50 From the rod 53, the cables pass upwardly to guide pulleys 55 which are rotatably mounted in a casing 56 disposed above the supporting member 9 and of such form that it may fit readily around the mast and 55 slide thereon when it is to be adjusted. After passing over the guide pulleys 55, the cables 52 extend downwardly through the member 9 and between the same and the mast to a guide roller 57 mounted on the 60 under side of projections 58 disposed in the same horizontal plane as the projections 54, but at the opposite side of the mast, and on the upper sides of said projections I mount a drum or windlass 59, the shaft of 65 which is provided with cranks or operat-

ing handles 60 at its ends. A pin or bolt 61 is inserted through the casing 56 and openings provided therefor in the mast so that the pulleys will be supported above the derrick-carrying member and will be prevented from dropping as will be understood. 70

It is thought the use of the apparatus will be readily understood. After the foundation for the silo has been formed and has sufficiently set, the lowermost section of the 75 mast, or two sections of the same spliced together, if desired, is set up by engaging the lower end thereof in the anchor block, as previously stated. The derrick and platform carrier is fitted over the mast and the 80 pulley casing secured to the mast above said carrier. The platform supports being engaged in the bands 14 and the platform boards laid on said supports, the derrick is properly adjusted and the device is ready 85 for use. When the wall of the silo has risen to a point where the mason cannot reach the upper course to be laid, the pin 30 is withdrawn and the windlass 59 operated to wind the cables 52 thereon. An upward pull will 90 be consequently exerted through the cables and the rod 53 upon the derrick and platform carrier so that the same will be caused to move vertically upward upon the mast and this vertical movement may continue 95 until the platform has been brought to the level of the finished wall or the upper extremity of the derrick-supporting member 9 reaches the casing 56. In the latter event, the casing 56 is adjusted to a higher point in 100 the mast, the derrick and platform carrier being prevented from dropping by the replacement of the bolt or pin 30. As the work progresses additional sections may be spliced to the mast and this operation will 105 be repeated until the silo has reached the desired height. To prevent sagging or bending of the mast as the platform and the derrick approach the upper end thereof, I provide blocks 62, indicated in dotted lines in 110 Fig. 1, which are clamped at intervals about the mast below the platform supports as said supports are brought to successive higher levels and to the said blocks I secure braces 63 likewise shown in dotted lines 115 which extend outwardly and slightly upwardly to engage against the inner surface of the completed silo wall below the platform supports, thereby bracing the mast and maintaining the true vertical position of the same. When the platform is to be raised, the locking levers 24 are released from the wall of the silo by exerting an upward pull upon the locking bars 25, the pins 27 being temporarily withdrawn, and it will be 120 understood that in placing the platform boards upon the scaffold or platform supports they may be laid so that the ends of the locking bars will be readily accessible. When the silo has reached the desired 125 130

height, the derrick will be drawn inwardly by shortening the connecting brace 36 so that the standards 35 will be swung close to the mast and the beam 38 drawn within the silo. The derrick may then be lowered within the silo and this lowering operation is accomplished by reversing the steps performed to raise the derrick and platform as the silo was built, the blocks 62 and braces 63 being removed as they are successively met by the descending platform supports and the several sections of the mast being disjointed and taken down as the lower levels are reached.

15 It will be readily noted from the foregoing description, taken in connection with the accompanying drawings, that I have provided an apparatus of inexpensive construction which will support the workmen within the silo where they may perform their labors most conveniently and advantageously. The position of the scaffold and the derrick may be easily shifted as the work progresses so that the workmen will follow the progress of the work without trouble and inconvenience. The derrick beam will be so adjusted that the building blocks or stones will be hoisted just outside the wall of the silo and will be so supported that the mason will be required merely to guide them into their proper places.

20 25 30

Having thus described my invention, what is claimed as new is:

1. In an apparatus for the purpose set forth, the combination of a mast, a carrier mounted thereon for vertical movement and provided with upper and lower annular series of sockets, the upper sockets having overhanging lips, and scaffold supports provided at their inner ends with upper and

lower tongues to engage in said sockets and upstanding hooks on the upper tongues to engage behind said overhanging lips.

2. An apparatus for the purpose set forth comprising a mast, a carrier mounted for vertical movement thereon, and scaffold supports detachably engaged in the carrier and radiating therefrom, some of said supports being provided with lever braces pivotally attached to their lower portions, and locking bars pivoted to said braces and adjustably secured to the upper members of the scaffold supports.

3. An apparatus for the purpose set forth comprising a mast, a carrier mounted thereon for vertical movement and provided with annular grooves, heads fitted in said grooves for rotary movement about the carrier, connections between the heads whereby they will be relatively fixed, a derrick carried by the lower of said heads, means on said head for operating the derrick, and an adjustable connection between the upper head and the derrick.

4. An apparatus for the purpose set forth comprising a mast of angular cross-section, a carrier mounted upon the mast for vertical movement and having a bore of cruciform cross section whereby portions thereof will be spaced from the sides of the mast, a guide adjustably secured to the mast above the carrier, a cable passing around said guide and through the carrier at the side of the mast, one end of said cable being fixed to the carrier, and means on the carrier attached to the opposite end of the cable for winding or unwinding the same.

In testimony whereof I affix my signature.

CARL C. YOUNG. [L.S.]
